DESIGN FOR A RUG

Ignatius J. Vetter, New York, N. Y., assignor to Bigelow Sanford Carpet Co., Inc., a corporation of Massachusetts

Application October 25, 1933. Serial No. 49,556

Term of patent 7 years

To all whom it may concern:

Be it known that I, IGNATIUS J. VETTER, a citizen of the United States, and resident of New York, in Bronx County and State of New York, have invented a new, original, and ornamental Design for a Rug, of which the following is a specification. Reference is had to the accompanying drawing, in which a plan view of the rug is shown.

I claim:

The ornamental design for a rug, substantially as shown.

IGNATIUS J. VETTER.
